UNITED STATES PATENT OFFICE

2,533,684

PULVERIZING MILL OF THE ROLLING
MORTAR TYPERichard L. Newcomb and Charles Jefferson
Harrah, Denver, Colo.

Application August 4, 1947, Serial No. 765,940

3 Claims. (Cl. 241—109)

1

This invention relates to a rock and ore crushing and grinding device and has for its principal object the provision of a simple and highly efficient grinding device which will have an exceedingly high capacity; which can be constantly and continuously controlled to regulate the fineness of grinding; which will be economical in power consumption; which can be constructed in any desired size; and which will be long wearing and not affected in its efficiency by wear of the grinding elements.

Another object of the invention is to provide a pulverizing mill of the rolling mortar type in which the axes of the pulverizing rollers will be positioned tangent to a circle surrounding the axis of the mill and not radial to the latter axis, so that the material to be crushed and pulverized will be attacked upon an angle or incline from a radial line to obtain a more efficient pulverizing action.

A further object of the invention is to provide dragging elements in a mill of this character which can be varied as to angle of attack while the mill is in operation so as to control the rate of flow of the material being pulverized toward the periphery of the mill.

A still further object is to provide a circular rolling pulverizing mill of the mortar type in which electric cars traveling upon an endless circular peripheral track may be used for the motive power.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a partial plan view of the improved grinding device. The portion not illustrated is simply a repetition of the portion illustrated.

Fig. 2 is a vertical section taken along the line 2—2 of Fig. 1.

Fig. 3 is a fragmentary detail section taken on the line 3—3, Fig. 2.

Fig. 4 is a side view of a power car employed in the improved grinding device.

2

Fig. 5 is an enlarged detail section taken on the line 5—5, Fig. 1.

The invention comprises a circular floor 10 preferably formed of relatively heavy steel plates secured to and supported by a suitable concrete foundation 11. A pair of endless, spaced-apart, track rails 12 surround the circular floor 10 supported upon suitable track ties 13. A plurality of power cars are arranged to travel around the track rails 12, upon suitable flanged track wheels 15 driven by means of electric motors 16, through suitable transmission devices as indicated at 17.

The cars 14 support the extremities of four spoke beams 18, which extend radially across the entire floor 10 at 90° intervals. The beams 18 are not secured to the trucks, but simply rest upon supporting rollers 42 on the cars and between two series of pushing rollers 23 so that any eccentricity in the tracks 12 will not effect the concentricity of the wheel.

The spoke beams are secured at their axial extremities between annular hub plates 19 surrounding the axis of a center pedestal 20. A plurality of intermediate beams, which will be herein designated as spokes 21, extend outward from the hub plates 19 between the spoke beams 18. The spoke beams 18 and the spokes 21 are tied together at equally spaced intervals by means of tie beams 22 so that the entire assembly forms a large, flat spoked wheel supported at its periphery by the cars 14. The wheel is supported at the axis by means of supporting rollers 43 which ride around a shoulder 44 on the pedestal 20. The wheel is maintained concentric by means of axial bearing rollers 24 which ride about an axial bearing surface 25 on the pedestal 20.

A plurality of pairs of roller links 26 are hingedly mounted on each of the beams 18 and spokes 21. The links 26 are mounted at their upper extremities upon hinge pins 45 which extend between bearing plates 46 supported below the spoke beams 18 and spokes 21 by means of angle hangers 47.

A plurality of relatively heavy crushing rollers 27 are rotatably mounted on roller shafts 48 extending between the extremities of the pairs of links 26 so as to trail behind the arms and beams and roll upon the floor 10. The crushing rollers 27 are arranged in staggered relation, so that every portion of the floor 10 within the circular paths of the rollers will be subjected to

their crushing action. The material to be crushed is fed into a receiving hopper 28, from which it flows to the floor 10 through a plurality of discharge chutes 29.

The material being crushed is swept toward the circumference of the floor 10 by means of drags 30 which trail from the cross beams 18. The drags 30 are arranged in pairs. The outer extremity of each drag of each pair is hingedly secured to one of the roller arms 26, such as by means of chain links 31. The inner extremities of the drags of each pair are secured to the opposite extremities of a cable 32. The cables 32 are wound intermediate their extremities about cable drums 33 which can be reversibly rotated by means of motors 34 mounted on floors 39 on the cross beams 18. The extremities of the cables 32 are led through guide tubes 35 extending through the supporting floors 39 from the beam 18 to the drags 30.

It can be seen that if the drums 33 are rotated in one direction, they will act to pull the inner extremity of the outer drag forwardly and allow the outer extremity of the inner drag to trail rearwardly so as to incline the drags to cause them to plow the material being ground toward the periphery of the floor 10. The angle of incline of the drags can be regulated by means of the motors 34. In fact, the incline can be reversed so that material can be worked inwardly for re-grinding, if desired.

The ground material is gradually dragged or scraped to the circumference of the floor 10, where it falls into an annular trough 36 surrounding the floor. A plurality of scrapers 37 suspended from the beams 18 on angle hangers 49 move around the circular trough 36, dragging the material to one or more sunken screw conveyors 38, which discharges to any suitable receiver.

The current to operate the motors 16 and 34 is conveyed to the rotating portions of the crusher through the medium of suitable electrical conductors 41 in a hollow center post 40 through the medium of suitable collecting rings and brushes (not shown), such as are conventionally used in conducting current to rotating equipment. Suitable electrical controllers are of course placed in circuit with the various motors to control their speed and direction.

It is desired to call attention to the fact that the axes of the rollers 27 are not radial. They travel parallel to the spoke members of the wheel and trail behind the latter. This arrangement is for the specific purpose of imparting a double action to the crushing rollers. They not only roll about the axle shafts 48, but they are also constantly moved longitudinally of their axis by the outwardly swinging movement of the rearwardly trailing roller links 26. This gives a combined rolling or crushing action and a sideward movement or abrading action which greatly increases the speed and efficiency of the grinding and crushing effect.

The bearing plates 46 bear against the sides of the links 26 and prevent them from swinging sideward. This forces the crushing rollers to move sidewardly as they rotate.

The floor 10 can be made in any desired diameter. A diameter of 40 feet has been found to be practical where large capacities are required. While the steel illustrated has eight spoke members, it is to be understood that this is simply illustrative. It could have either more or less, depending upon the capacity desired.

The hopper 28 is supported on legs 50 from the

upper hub plate 19 and is formed integrally with a central bearing sleeve 51 which is rotatably mounted about the center post 40. Thus, the hopper rotates with the grinder. On the cars 14 the power is transmitted from the transmission device 17 independently to the wheels by means of suitable belts 52 riding over belt pulleys 53.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. An ore grinding machine comprising: a circular, horizontal floor; a pedestal arising at the axis of said floor; a circular track concentrically surrounding said floor; hub members rotatably mounted on said pedestal; cross beams extending from said hub members radially outward over said track; cars mounted on said track, there being one car under the projecting extremity of each cross beam; means projecting upward from each car into engagement with the cross beam thereabove to propel the latter driving motors on said cars; pairs of equal-lengthed hinged roller links extending rearwardly from each cross beam; a crushing roller mounted between each pair of roller links so as to roll upon said floor with its axis spaced from and parallel to the adjacent beam; means for feeding material to be crushed to said floor adjacent the axis thereof; means for conveying the material being crushed toward the circumference of said floor; and means for maintaining said links at right angles to said beams so that the axes of said rollers will be maintained at acute angles to radii extending through the rollers.

2. An ore grinding machine comprising: a circular, horizontal floor; a pedestal arising at the axis of said floor; a circular track concentrically surrounding said floor; hub members rotatably mounted on said pedestal; cross beams extending from said hub members radially outward over said track; cars mounted on said track, there being one car under the projecting extremity of each cross beam; means projecting upward from each car into engagement with the cross beam thereabove to propel the latter driving motors on said cars; two pairs of hinged roller links extending rearwardly from each cross beam; a pair of crushing rollers, there being a crushing roller mounted between each pair of roller links so as to roll upon said floor; means for feeding material to be crushed to said floor adjacent the axis thereof; an elongated drag member hingedly secured to the outer roller links of the outer roller of each pair and extending inwardly toward the axis of the floor rearwardly of said roller; an inner drag member secured to the inner roller links of the inner roller of each pair and extending outwardly toward the circumference of said floor; a cable having its extremities secured to the adjacent free extremities of said drag members; and a motor-operated reel about which the mid-portion of said cable is wrapped, so that rotation of said reel will incline both drag members simultaneously in a common direction.

3. A pulverizing mill comprising: a horizontal circular floor; a vertical pedestal at the axis of said floor; a plurality of horizontal radial arms adapted to rotate about said pedestal; a pair of crushing rollers positioned on said floor behind

each arm; hinged links connecting said rollers to the adjacent arm; an elongated drag member positioned behind each roller of each pair of rollers in substantially longitudinal alignment with each other; hinge means securing the distant extremities of said drag members to the distant links of a pair of rollers; a cable extending from the adjacent extremity of one drag member to the adjacent extremity of the other drag member; and cable-reeling means mounted on the arm between said rollers, said cable passing about and being secured to said cable-reeling means intermediate the extremities of said cable so that rotation of said cable-reeling means will swing the adjacent extremities of each pair of drag members in opposite directions.
